DECK LID LOCK

Algott L. Nelson, Detroit, Mich., assignor to Ternstedt Manufacturing Company, Detroit, Mich., a corporation of Michigan

Application January 22, 1940, Serial No. 314,945

7 Claims. (Cl. 292—126)

This invention relates to a lock for the rear deck lid of an automobile.

In the present day automobile the rear deck lid is a sheet steel stamping hinged to the body at its forward or upward edge. The deck lid extends rearwardly and downwardly from the hinges and usually terminates in quite a sharp or substantially vertical curve at its rear. The deck lid when closed presses down upon, and is sealed completely around its periphery by a rubber weatherstrip. Due to the fact that the deck lid is a thin sheet steel stamping having the above described curvature, the lid tends to crinkle if not provided with the correct lock.

It is the object of this invention to produce a simple deck lid lock which will draw the lid into sealing relation with the weatherstrip and place the lid under tension rather than compression and thereby avoid crinkling of the lid when locked.

In the drawings:

Fig. 1 is an elevation of the deck lid lock in locked position as viewed from without the rear deck compartment looking toward the front of the vehicle.

Fig. 2 is a view along the line 2—2 of Fig. 1.

Fig. 3 is a view along the line 3—3 of Fig. 2.

Fig. 4 is a view along the line 4—4 of Fig. 3.

Fig. 5 is a view along the line 5—5 of Fig. 3.

Fig. 6 is a view similar to Fig. 2 showing the relation of the parts when the lock is unlocked.

Fig. 7 is a view similar to Fig. 1 showing the relation of the parts when the lock is unlocked.

Fig. 8 is a vertical section through the deck lid and lock showing the deck lid in locked position.

Fig. 9 is a view similar to Fig. 8 showing the lock unlocked.

Figs. 10 and 11 are vertical sections through the deck lid and lock showing the relation of the parts in various stages of locking.

Figs. 12 and 13 are detail views of a slightly modified form of lock.

Referring more particularly to the drawings, there is shown a portion of the rear deck of an automobile body comprising outside sheet metal panel 1 and inner sheet metal panel 2. The lid is provided with an overlap flange 3 (Fig. 8) which presses and seals against a rubber weatherstrip 4 which extends completely about the periphery of the opening in the rear deck 5. Figs. 8 through 11 show the lower horizontal edge of the deck lid, that is, the end most remote from the front edge, not shown, which is hinged to the body.

The deck lid locking arrangement comprises a pair of locks operated by a single deck lid handle 6. Only one lock will be described because the two locks are identical. The lock comprises a support plate 8 which is fixed to the inner panel 2 in any suitable manner, such as by weld-

ing or bolts. The plate 8 has a vertical flange 7 which projects outwardly from the inner panel 2, as shown in Fig. 2.

The latch bolt is designated 9 and the bolt head takes the form of a hook 10. The bolt 9 is positioned between the legs 11 and 12 of the yoke 13 and pivoted on pin 14 which is fixed to legs 11 and 12. A pin 22 is journaled in flange 7. Yoke 13 is fixed to pin 22 on one side of the flange 7 and lever 23 is fixed to the yoke on the other side of the flange. The bolt is biased downwardly by spring 15 carried on pin 14, the lower end 16 of which hooks over bolt 9. The bolt 9 is provided with lug 17 which abuts corner 18 of flange 7 to limit the downward swinging of bolt 9 when the lid is raised and the bolt head 10 disconnected from its keeper 19. The keeper 19 is fixed to bracket 20 which is fixed to the rear deck panel 5 adjacent the lower edge of the rear deck opening 21.

The swinging of each bolt is effected by rotation of handle 6. Handle 6 is journaled in a bracket 24 fixed to the inside lid panel 2. A lever 25 is fixed on the handle spindle 26. A pair of links 27 connect the lever 25 with levers 28 which are pivotally mounted on plate 7 by means of pins 29. Link 30 connects lever 28 with lever 23.

In Figs. 1 and 8 the lock is shown in locked position with the bolt head 10 interengaged with keeper 19. To open the lid the handle 6 is turned so that lever 25 rotates counterclockwise, Fig. 1. The push thus exerted on links 27 causes the lever 28 on each lock to swing clockwise, Fig. 3, which, through link 30, swings lever 23 counterclockwise as viewed in Fig. 4. This causes yoke 13 to swing counterclockwise, Fig. 4, whereupon the yoke strikes the tail 32 of bolt 9 causing it to rotate counterclockwise and disengage the bolt head 10 from the striker as shown in Fig. 9.

The locking of the lid is effected as follows: The lid is closed until it rests against the weatherstrip 4. At this time the lid is usually not completely closed as illustrated in Fig. 10. The position of the handle and lever 25 is illustrated in Fig. 7. To lock the lid the handle 6 is rotated so that the lever 25 rotates clockwise, Fig. 7, thus pulling on links 27 which turn levers 28 clockwise, Fig. 7, thereby drawing links 30 upwardly. As link 30 is drawn upwardly yoke 13 rotates about pivot 22 clockwise, as viewed in Fig. 10, thus raising pivot 14, the point at which bolt 9 is connected to yoke 13. At this time, as shown in Fig. 10, pivot 22 is positioned above pivot 14. As pivot 14 rotates clockwise about fixed pivot 22, bolt 9 is drawn toward the left and upwardly, Fig. 10, which causes the bolt head 10 to swing downwardly into engagement with the keeper 19, as shown in Fig. 11. Further rotation of yoke 13 causes the lid 1 to be pulled first inwardly until pivot point 14 is on the same level as pin 22, Fig. 11, whereupon further clockwise rotation of yoke

13 causes the lid 1 to be drawn downwardly into tight engagement with the weatherstrip 4, as shown in Fig. 8. It should be noted that after the hook 10 engages striker 19 that bolt 9 rotates about pin 14 relative to yoke 13. In final locked position pivot point 14 is over the center line passing through the center of pivot 22 and the point at which bolt head 10 contacts striker 19, see Figs. 5 and 8. Due to this over center locking arrangement any attempt to force the lid 1 open merely tends to rotate yoke 13 clockwise, Fig. 8, thus tightening the interengagement between the bolt head and the striker. The bolt can only be disengaged from the keeper 19 by rotating yoke 13 counterclockwise, Fig. 8, to again bring pivot 14 to the left of center, that is, a line passing through pin 22 and the point at which the bolt head 10 interengages the striker, as illustrated in Fig. 8.

In the modified form shown in Figs. 12 and 13 there is provided a simplified form of connection between the levers 28 and the yoke 13. In this form of the invention the support plate 40, corresponding to plate 7, is provided with a flange 41. Pin 42 is riveted at one end to flange 41 and carries a bushing 43. Yoke 13 is rotatably supported on the outer end of pin 42. Pivot 42 corresponds to pivot 22 of the principal form of the invention. Link 44, corresponding to link 30, is pivotally connected at one end to lever 28 and the other end of link 44 is pivoted to yoke 13 by pin 14. Pin 14 also pivotally supports bolt 9 on yoke 13. The operation of the lock is identical with that shown in the principal form of the invention.

It will be noted that when the bolt head 10 is interengaged with the keeper 19 that the bolt 9 swings about the keeper 19 as a center during the final locking movement of the bolt and during the initial opening movement of the bolt.

I claim:

1. In an automotive vehicle having a deck with an opening therein and a deck lid hinged at its forward edge for closing the said opening and a keeper mounted along the bottom edge of said opening, a support plate fixed to the inside face of said lid adjacent its lower edge, a yoke pivoted on said support plate, a bolt pivoted on said yoke between the legs of the yoke, the pivot for said bolt swinging about the pivot for said yoke as a center, the said bolt having a head adapted to pivotally interengage said keeper, means for rotating said yoke to interengage the keeper and bolt head and swing the pivotal connection between the yoke and bolt over center past a line passing through the pivot for said yoke and the point of interengagement of said keeper and bolt head whereby the deck lid is drawn downwardly and inwardly into fully closed position.

2. In an automotive vehicle having a deck with an opening therein and a deck lid hinged at its forward edge for closing the said opening and a keeper mounted along the bottom edge of said opening, a support plate fixed to the inside face of said lid adjacent its lower edge, a member pivoted on said support plate, a bolt loosely pivoted on said member, the pivot for said bolt swinging about the pivot for said member as a center, the said bolt having a head adapted to pivotally interengage said keeper, means for rotating said member to interengage the keeper and bolt head and swing the pivotal connection between the member and bolt over center past a line passing through the pivot for said member and the point of interengagement of said

keeper and bolt head whereby the deck lid is drawn downwardly and inwardly into fully closed position.

3. A lock for the deck lid of an automobile comprising a support plate, a member pivoted on said plate, a bolt having a tail and head eccentrically and freely pivoted between its tail and head on said member, means for rotating said member in a first direction whereby the said bolt is projected and said bolt head describes an arcuate path and means for rotating said member in a second direction whereby said member engages the tail of the bolt to pivot and retract the same.

15 4. A lock for the deck lid of an automobile comprising a support plate, a member pivoted on said plate, a bolt having a tail and head eccentrically and freely pivoted between its tail and head on said member, means to rotate said member whereby said bolt is projected and said pivot for said bolt swings about the pivot for said member to lock said bolt in an over center position and means for rotating said member in a second direction whereby said member engages the tail of the bolt to retract the same.

20 5. A lock for the deck lid of an automobile comprising a support plate, a member pivoted on said plate, a bolt having a tail and head eccentrically and freely pivoted between its tail and head on said member, means for rotating said member in a first direction whereby the said bolt is projected and said bolt head describes an arcuate path, means for rotating said member in a second direction whereby said member engages the tail of the bolt to pivot and retract the same and resilient means biasing said bolt toward projected position.

25 6. A lock for the deck lid of an automobile comprising a support plate, a member pivoted on said plate, a bolt having a tail and head eccentrically and freely pivoted between its tail and head on said member, means to rotate said member whereby said bolt is projected and said pivot for said bolt swings about the pivot for said member to lock said bolt in an over center position, means for rotating said member in a second direction whereby said member engages the tail of the bolt to retract the same and resilient means biasing said bolt toward projected position.

30 7. In an automobile vehicle having a deck with an opening therein and a deck lid hinged at its forward edge for closing the said opening and a keeper mounted along the bottom edge of said opening, a lock comprising a support plate fixed to the inside face of said lid, a member pivoted on said plate, a bolt having a tail and head eccentrically and freely pivoted between its tail and head on said member, the pivot for said bolt swinging about the pivot for said member as a center, the said bolt having a head adapted to pivotally interengage said keeper, means for rotating said member in one direction to interengage the keeper and bolt head and swing the pivotal connections between the member and bolt over center past a line passing through the pivot for said member and the point of interengagement of said keeper and bolt head whereby the deck lid is drawn downwardly and inwardly into fully closed position, and means for rotating said member in a second direction whereby the said member engages the tail of the bolt to rotate and retract the same.
